UNITED STATES PATENT OFFICE.

HERBERT G. BEEDE, OF PAWTUCKET, RHODE ISLAND.

RING SPINNING OR TWISTING APPARATUS.

1,075,004.

Specification of Letters Patent.

Patented Oct. 7, 1913.

Application filed November 6, 1912. Serial No. 729,711.

To all whom it may concern:

Be it known that I, HERBERT G. BEEDE, a citizen of the United States, residing at Pawtucket, in the county of Providence and 5 State of Rhode Island, have invented certain new and useful Improvements in Ring Spinning or Twisting Apparatus, of which the following is a specification.

My invention relates to ring spinning or 10 twisting apparatus, and more particularly to the ring and traveler, employed in ring spinning or twisting.

The object of my invention is to provide 15 a ring and traveler for ring spinning or twisting, and more particularly a ring and traveler for spinning and twisting heavy yarns, twine, etc.

My invention consists in certain novel 20 features of construction of my improvements in ring and traveler for spinning and twisting apparatus, as will be herein-after fully described.

Referring to the drawings:—Figure 1 is 25 a plan view of a ring and traveler, and connected parts, embodying my improvements, partially broken away on the left of the figure. Fig. 2 is a section, on line 2, 2, Fig. 1, looking in the direction of arrow *a*, same figure; the parts broken away in 30 Fig. 1 are shown in this figure. Fig. 3 is a section, on line 3, 3, Fig. 1, looking in the direction of arrow *b*, same figure. Fig. 4 corresponds to Fig. 2, but shows a different position of the friction member. Fig. 35 5 corresponds to Fig. 1, but shows a modified construction. Fig. 6 shows the broken away parts shown at the left in Fig. 5, with the friction member in its opposite position. Fig. 7 is a section, on line 7, 7, Fig. 5, 40 looking in the direction of arrow *c*, same figure; the part broken away in Fig. 5 is shown in this figure. Fig. 8 is a section, on line 8, 8, Fig. 6, looking in the direction of arrow *d*, same figure; the part broken away 45 in Fig. 6 is shown in this figure. Fig. 9 corresponds to Fig. 5, but shows a modified construction. Fig. 10 shows the broken away parts shown at the left in Fig. 9, with the friction member in its opposite position. Fig. 11 is a section, on line 11, 11, Fig. 9, looking in the direction of arrow *e*, same figure; the part broken away in Fig. 9 is shown in this figure. Fig. 12 shows a modified construction of the parts shown 50 in Fig. 11. Fig. 13 corresponds to Fig. 1,

but shows a modified construction. Fig. 14 is a section, on line 14, 14, Fig. 13, looking in the direction of arrow *f*, same figure; the parts broken away in Fig. 13 are shown in this figure, and, Fig. 15 corresponds to Fig. 12, but shows a modified construction.

In the accompanying drawings, referring to Figs. 1 to 4, inclusive, 1 is the rail of a spinning or twisting frame, provided with a circular opening 1' therethrough, through 65 which extends the spool or bobbin, not shown, on which the yarn of twine is to be wound. Upon the rail 1 is a stationary ring 2, the internal diameter of which corresponds to the diameter of the opening 1' 70 in the rail 1. The ring 2 has upon its upper surface a recess 2' in this instance of right angle shape in cross section, and upon its inner edge a bevel surface, see Fig. 2. Extending within the recess in the upper 75 part of the ring 2 is a ring 3, the lower inner edge of which has a bevel surface 3', see Fig. 2. The ring 3 is removably attached to the ring 2, in this instance by four screws 4. The screws 4 extend loosely 80 through holes in the ring 3, and also loosely through holes in the ring 2, and are screwed into the rail 1, see Fig. 2, to secure the ring 3 to the ring 2, and the ring 2 to the rail 1.

With the ring 2 and ring 3 is combined 85 my improved traveler, which consists of a ring 5, loosely mounted over the opening 1' in the rail 1, within the stationary rings 2 and 3, to have a rotary motion. The ring 5 preferably has an outwardly extending 90 flange 5', on its upper and lower edge, forming a recessed portion or portions in the periphery of the ring. Combined with the recessed portion or portions of the ring 5 are friction members or devices, which extend into a recessed portion in the inner edges of the stationary rings 2 and 3, and act to support the rotary ring 5, and maintain it in its horizontal position. The ring 5 has in this instance 2 yarn guide eyes 6, 95 secured upon the top edge thereof, on opposite sides, see Fig. 1. The supporting and friction members, shown in Figs. 1 to 4, inclusive, comprise four blocks 7, extending within the recessed periphery of the ring 5, and arranged at equal distances apart. The outer edge of the movable friction blocks 7 is of wedge shape, to extend into the wedge shaped recess on the inner edge of the stationary rings 2 and 3, as shown in Fig. 2. 100 105 110

In connection with the four loose friction blocks 7 are four parts 8, which are stationary relative to the ring 5, and each secured within the recessed periphery thereof, in this instance by three pins or rivets 9, see Fig. 3. The parts 8, secured to the ring 5, have a wedge shaped outer edge, to extend loosely in the V shaped recess in the inner edge of the stationary rings 2 and 3, as shown in Fig. 3, and act to support the rotary ring 5 and maintain it in its horizontal position, and also act to space and hold in proper position the movable friction members 7. The rotation of the movable traveler ring 5, carrying with it the loose friction members 7, will cause said friction members to have a centrifugal action and move out and away from the ring 5, to enter and engage the recessed part on the inner edge of the stationary rings 2 and 3, as shown in Fig. 2, to increase the friction and retard the rotary movement of the ring 5. When the ring 5 is stationary, the friction members 7 will be in their inward position, as shown in Fig. 4.

I will now describe the modified construction shown in Figs. 5 to 8, inclusive. The same reference numerals are used in these figures for corresponding parts as in Figs. 1 to 4, inclusive. In Figs. 5 to 8 inclusive, instead of the loose friction member or block 7, a block 7^a, pivotally attached at one end by a pin 7^a' within the recessed periphery of the movable ring 5, is used, see Figs. 5 and 6. In Figs. 5 and 7, the pivotally mounted friction member or block 7^a is shown in its outward position. In Figs. 6 and 8, the block 7^a is shown in its inward position.

I will now describe the modified construction shown in Figs. 9 to 12, inclusive. There are three pivotally attached friction members or blocks 7^c in said figures, instead of four, shown in Fig. 5, and said friction members 7^c have a straight surface with square corners on their outer engaging edge, to loosely enter a recess with square corners in the inner edge of the stationary rings 2 and 3, as shown in Fig. 11, and the inner surface of the friction members 7^c are recessed or hollowed out. Between the members 7^c, within the recessed periphery of the movable ring 5, there are no members 8 connected to the movable ring 5, as shown in the previous figures. In Fig. 12, the friction member 7^d, corresponding to the friction member 7^c, has a wedge shaped outer surface, to engage the V shaped recess in the inner surface of the stationary rings 2 and 3.

In the modified construction shown in Figs. 13 and 14, a series of spherical surfaces or balls 7^e, loosely retained within the recesses or notches 5^{ee} in the outer edge of the movable ring 5, form the friction members

corresponding to the friction members shown in the figures of the drawings hereinbefore described.

In the modified construction shown in Fig. 15, a cylindrical shaped member or roll 7^f is substituted for the spherical shaped members or balls 7^e.

The advantages of my improvements in ring traveler for ring spinning or twisting will be readily appreciated by those skilled in the art.

My ring traveler is particularly used in spooling heavy twisted yarn or twine, as it comes from the twisting machine, and in which a large sized and heavy traveler is used, and the drag on the yarn is increased by means of the friction members which are connected with, and rotate positively with the traveler, and engage with the stationary ring within which the traveler rotates.

It will be understood that the details of construction of my improvements may be varied if desired.

Having thus described my invention, what I claim as new and desire to secure by Letters Patent is:

1. In ring spinning or twisting apparatus, the combination with a stationary ring, of a rotatable ring or traveler, to rotate within said stationary ring, and movable friction members, intermediate said stationary ring and said movable ring or traveler, said movable friction member connected with, and rotating positively with said rotatable ring or traveler.

2. In ring spinning or twisting apparatus, the combination with a stationary ring, of a rotatable ring or traveler, to rotate within said stationary ring, and movable supporting and friction member, intermediate said stationary ring and said movable ring or traveler, said movable supporting and friction members connected with, and rotating positively with said rotatable ring or traveler.

3. In ring spinning or twisting apparatus, the combination with a stationary ring, of a rotatable ring or traveler, to rotate within said stationary ring, and movable friction members connected with and rotating positively with said rotatable ring or traveler.

4. In ring spinning or twisting apparatus, the combination with a stationary ring having a recessed inner edge, and a second stationary ring having a recessed inner edge, and removably attached to said first mentioned ring, of a rotatable ring, or traveler extending within said two rings, and having a recess or recesses in its periphery, and movable friction members or devices extending within said recess or recesses in said rotatable ring, and also extending within the recessed inner edges of said first mentioned stationary rings.

5. In ring spinning or twisting apparatus, the combination with a stationary ring, having a recessed inner edge, and a second stationary ring having a recessed inner edge, and removably attached to said first mentioned ring, of a rotatable ring or traveler extending within said two rings, and having a recess or recesses in its periphery, and movable friction members or devices con-

nected with said rotatable ring and extending within said recess or recesses in said rotatable ring, and also extending within the recessed inner edges of said first mentioned stationary rings. 10
